ASSIGNORS TO MONITOR DRILL COMPANY, OF MINNEAPOLIS, MINNESOTA, A COR-
PORATION OF MINNESOTA.

DISK ATTACHMENT.

1,130,699.

Specification of Letters Patent.

Patented Mar. 9, 1915.

Application filed August 28, 1914. Serial No. 859,040.

To all whom it may concern:

Be it known that we, EDWIN R. BEEMAN and THOMAS BRENNAN, Jr., both citizens of the United States, residing at St. Louis 5 Park, county of Hennepin, and State of Minnesota, have invented certain new and useful Improvements in Disk Attachments, of which the following is a specification.

The present invention has reference to 10 certain improvements in disk attachments, and particularly to improvements in bearings for the same.

The invention has particular reference to 15 improvements in double disk attachments, and has for its main object to so improve the disk bearings of the same that the disks will more readily and perfectly adjust themselves and remain in contact with each other at all times. For this purpose it will be 20 understood that the disks are mounted with their planes or peripheral portions at an angle to each other, and that means must be provided for pressing the disks toward each other under a spring pressure, so that they 25 will be maintained with their edges in contact at the proper point at all times, regardless of changes in the diameter of the disks owing to their wear in service.

Another object of the invention is to so 30 construct the disk bearing that it can be readily assembled, and to so construct it that either disk can be readily removed when the occasion requires, so that the farmer can readily substitute another pair 35 of disks.

Other objects and uses will appear from a 40 detailed description of the invention, which consists in the features of construction and combinations of parts hereinafter described and claimed.

In the drawing Figure 1 shows a vertical elevation of a disk attachment provided 45 with a bearing embodying the features of the present invention, the disk on the near side of the boot being cut away on the line 1—1 of Fig. 2; and Fig. 2 is a longitudinal section taken on the line 2—2 looking in the direction of the arrows, this being the diameter of the disks which includes the point 50 of contact between them.

The frame 3 of the disk attachment may be made in the usual and customary manner, being provided with a downwardly depending boot 4. At its lower end this boot

carries the rod or tube 5 which constitutes 55 an axle and which has its end portions bent in the proper directions to constitute bearings on which the sleeves or bushings may slide back and forth in their adjustment. The plane which includes the bent end portions of the axle 5 is the plane which includes the point of contact between the 60 edges of the disks.

On each of the end portions of the axle 5 we slidably mount a sleeve or the like 6. 65 The outer end of each sleeve is provided with an annular flange 7, behind which is a slot or groove 8 adapted to receive a cotter pin or the like 9. Each cotter pin is extended through holes in the end of the axle 70 5. Inasmuch as the said axle is rigidly secured to the boot so that it cannot rotate, it follows that the sleeves are likewise retained against rotation, although they may adjust themselves in and out along the end 75 portions of the axle 5. In order to effect such adjustment, we have provided the spiral springs 10, the inner ends of which bear against the back sides of the annular flanges 7 and the outer ends of which bear 80 against washers 11, which are held in place by means of the cotter pins. Inasmuch as the sleeves and cotter pins do not rotate, it follows that there is no twisting or turning effort exerted on the springs. Each of the 85 sleeves has its inner portion tapered toward the boot and on each of these tapered portions is mounted a hub 12 for the corresponding disk 13. These hubs are suitably proportioned to bear against the annular 90 flanges 7, so that they will never bind on the sleeves but, on the contrary, will rotate freely on them.

The pressures exerted by the springs 10 will bring the disks together at the point 95 14 indicated in each of the figures. As the disks wear or are ground away in service, the hubs 12 will be pressed closer and closer toward each other, but the disks will always be maintained in contact under spring pressure. Furthermore, in case of any inequality in either of the disks, such as an imperfection in its manufacture or grinding, the disks will be free to adjust back and forth 100 with respect to each other as they rotate, 105 being held in contact at all times under spring pressure.

The customary cap or protector 15 may

be threaded onto each of the hubs 12 for the purpose of protecting the sleeves and other moving parts so that they will not become clogged or obstructed by dirt or dust.

5 From the foregoing it will be seen that whenever it is desired to remove either disk it is only necessary to remove the corresponding cap 15 and withdraw the corresponding cotter pin, whereupon the hub 10 and disk may be readily removed without in any manner interfering with the other disk and its bearing. It will also be noted from an examination of Fig. 2 that the sleeves 6 terminate short of the inner faces 15 of the hubs 12. By so proportioning the parts assurance is had that the sleeves will never come into binding contact with the boot as the disks wear down in diameter.

While we have herein shown and described only one form of construction embodying the features of our invention, nevertheless it will be understood that we include within the scope of our invention any other equivalent forms which may be covered by the claims.

We claim:

1. In a disk attachment, the combination with a downwardly depending boot, of an axle member carried by the lower end of the same and having its end portions projecting to the sides of the boot, a sleeve slidably mounted on each projecting end portion, the outer end of each sleeve being provided with a transversely extending slot, 30 a cotter pin or the like extended through each projecting end portion and lying within the slot of the corresponding sleeve, a spring interposed between each of said cotter pins and the corresponding sleeve and 35 serving to force the sleeve toward the boot, a peripheral flange on each sleeve, and a disk rotatably mounted adjacent to each sleeve and provided with a bearing portion adapted to rotate on the sleeve and seat against 40 the corresponding flange.

2. In a disk attachment, the combination with a downwardly depending boot, of an axle member supported by and projecting to each side of the boot, a sleeve slidably 50 mounted on each projecting end portion, means for forcing each sleeve toward the boot, means for retaining each sleeve against rotation, an annular flange encircling each sleeve near the outer end thereof, a disk rotatably mounted with respect to each sleeve, 55 and a bearing portion on each disk adapted to rotate on the corresponding sleeve and seat against the flange thereof.

3. In a disk attachment, the combination with a downwardly depending boot, of an axle member secured to and projecting to each side of the boot, a sleeve slidably mounted on each projecting portion of the axle member, means for retaining each sleeve against rotation with respect to the axle member, springs tending to carry the sleeves toward each other, each sleeve being provided with an annular projecting flange near its outer end, a disk rotatably mounted with respect to each sleeve, and a bearing portion on each disk, each bearing portion being adapted to rotate on the corresponding sleeve and seat against the flange thereof.

4. In a disk attachment, the combination with a downwardly depending boot, of an axle member secured to and projecting to the sides of the boot, a sleeve slidably mounted on each projecting portion of the axle member, means for retaining each sleeve against rotation with respect to the axle member, means for carrying the sleeves toward each other and toward the boot, each sleeve being provided with an annular projecting flange near its outer end and tapering in size toward its inner end, a disk rotatably mounted with respect to each sleeve and a bearing member on each disk rotatably mounted on the tapering portion of the corresponding sleeve and seating against the annular flange thereof.

5. In a disk attachment, the combination with a downwardly depending boot, of an axle member secured to and projecting to the sides of the boot, a sleeve slidably mounted on each end of the axle, means for retaining each sleeve against rotation with respect to the axle member, means for carrying the sleeves toward each other and toward the boot, an annular projecting flange 95 on each sleeve near the outer end thereof, a disk rotatably mounted with respect to each sleeve, a bearing member on each disk rotatably mounted on the corresponding sleeve, each sleeve tapering in diameter from the 100 annular flange toward the inner end thereof and the corresponding disk bearing member rotating on said tapered portion and being of a size to seat against the corresponding annular flange.
